DESIGN FOR A CARPET SWEEPER

Henry W. Gussack, New York, N. Y.

Application July 12, 1940, Serial No. 93,598

Term of patent 3½ years

To all whom it may concern:

Be it known that I, Henry W. Gussack, a citizen of the United States, residing in the city of New York, county of Kings, and State of New York, have invented a new, original, and ornamental Design for Carpet Sweepers, of which the following is a specification, reference being had to the accompanying drawing, forming part thereof.

Fig. I is a perspective view of a carpet sweeper showing my new design.

Fig. II is a top view thereof.

I claim:

The ornamental design for a carpet sweeper, as shown.

HENRY W. GUSSACK.
